UNITED STATES PATENT OFFICE.

WILTON H. DAVIS, OF CAMDEN, NEW JERSEY.

DISPLAY-CASE.

1,102,145.

Specification of Letters Patent. Patented June 30, 1914.

Application filed December 19, 1913. Serial No. 807,729.

To all whom it may concern:

Be it known that I, WILTON H. DAVIS, a citizen of the United States, residing at Camden, in the county of Camden and State 5 of New Jersey, have invented new and useful Improvements in Display-Cases, of which the following is a specification.

This invention relates to a display case, the object of the invention being to provide a 10 simple, and inexpensive construction of device for displaying advertising or other matter, which device may be arranged for observation within railway stations, hotels, and other public buildings for the general convenience of the traveling public.

A further object of the invention is to provide a display case which is of maximum simplicity of construction, inexpensive of 15 production, neat and ornamental in appearance, and which provides for the ready, easy and convenient insertion and removal of display cards when occasion requires.

The invention consists of the features of construction, combination and arrangement 20 of parts herein fully described and claimed, reference being had to the accompanying drawing in which:—

Figure 1 is a front elevation of a combined railway train schedule and advertising case embodying my invention. Fig. 2 is a similar view of the rear wall of the case. Figs. 3 and 4 are sections through the case taken respectively on the lines 3—3 and 4—4 of Fig. 1.

In carrying my invention into practice, I provide a frame or case 1, made of suitable material, and preferably of oblong rectangular form. This case 1 is provided with a rear wall 2 and a hinged front door 3, which 35 may be locked or fastened in closed position in any preferred manner. The said door 3 consists of a frame having a glass or other transparent panel 4 through which the interior of the casing may be viewed. Fitted 40 within the case against the back wall 2 is a mat 5, composed of cardboard or other suitable material, which mat is cut out to provide a main central display opening 6 and vertical rows of smaller display openings 7 on opposite sides thereof. The opening 6 is adapted for the display therethrough of a train schedule card or sheet 8, while the openings 7 are adapted for the display therethrough of individual advertising 45 cards 9. The train schedule may be printed

or otherwise suitably placed upon the card or sheet 8, and may indicate the arrival and departure of trains from and to any particular place or city, while the cards 9 may embody the advertisements of merchants 60 and others and display matter of general interest to tourists and the traveling public generally. The case may be hung upon the wall in a station, hotel or other public place for conspicuous display 65 and consultation. The sheet or card 8 is confined in position upon the front face of the back 2 of the case by thin sheet metal clamping strips 10, which are secured in place at their ends by tacks, screws or other 70 suitable fastenings 11, said strips being spaced a somewhat greater distance than the width of the opening 6 to receive the edges of the card or sheet 8 and clamp the same in position. The rows of cards 9 are individually secured in position on opposite sides of the pair of strips 10 by pairs of similar strips 12, which are however secured to the back 2 by rows of spaced fastenings 13. The free portions of the strips 12 between 75 the fastenings 13 are provided with right angularly bent tongues or flanges 14 to hold the edges of the cards 9 in position for display through the opening 7, the strips 10 holding the card or sheet 8 in position for 80 display through the opening 6, as will be readily understood. The cards or sheets 8 are applied by placing them in position between the holding strips and properly bowing them, so that opposed edges thereof 85 may be inserted beneath the strips, after which by releasing the cards they will straighten out, thereby bringing their edges into engagement with the tongues or flanges 14. By similarly bowing the strips the 90 edges of the cards may be withdrawn from engagement with the strips, allowing the cards to be readily removed.

It will be observed from the foregoing description that the invention provides a 100 frame case for the purpose specified which is simple of construction, neat and ornamental of appearance and inexpensive of production, and by means of which a train schedule and advertising or other matter 105 may be readily and conveniently displayed. From the construction disclosed it will also be obvious that upon opening the door 3 the mat 5 may be drawn outward, thus exposing the cards upon the back of the case, so that 110

the cards may be readily and conveniently applied and removed when occasion requires.

I claim:—

- 5 A display case comprising an oblong rectangular frame having a back wall and provided at the front with a hinged door having a transparent panel, a mat removably mounted in the frame between the back wall and door and provided with vertical rows of observation openings and pairs of holding strips arranged upon the back wall, the holding strips of each pair being secured to
- 10

the back at spaced intervals by fastenings and having their free portions between the fastenings bent to form flanges or tongues to engage and hold cards to be displayed through the said rows of observation openings.

In testimony whereof I affix my signature 20 in presence of two witnesses.

WILTON H. DAVIS.
